United States Patent Office

Des. 195,462
Patented June 18, 1963

195,462

RAZOR

Sam M. Baseel, 8221 Clayton Road, St. Louis, Mo.

Filed Oct. 12, 1962, Ser. No. 72,084

Term of patent 14 years

(Cl. D22—3)

FIG. 1.

FIG. 2.

FIG. 3.

FIG. 4.

FIG. 5.

I claim:

The ornamental design for a razor, substantially as shown and described.
